UNITED STATES PATENT OFFICE.

PAUL J. WIDERA, OF CHICAGO, ILLINOIS, ASSIGNOR OF ONE-HALF TO WLADYSLAW PIJAKOWSKI, OF CHICAGO, ILLINOIS.

GAS-BELL HANGER.

1,284,519.

Specification of Letters Patent. Patented Nov. 12, 1918.

Application filed January 14, 1918. Serial No. 211,788.

To all whom it may concern:

Be it known that I, PAUL J. WIDERA, a citizen of the United States, residing at Chicago, in the county of Cook and State 5 of Illinois, have invented certain new and useful Improvements in Gas-Bell Hangers, of which the following is a specification.

This invention relates to gas fixtures and has special reference to a gas bell hanger.

One object of the invention is to improve 10 and simplify the general construction of devices of this character.

A second important object of the invention is to provide an improved form of gas 15 bell hanger readily attachable to the vertical type of the gas fixture and wherein the arm supporting the gas bell may be set at one of a number of desired angles without the use of set screws or the like.

With the above and other objects in view, as will be hereinafter apparent the invention 20 consists in general of certain novel details of construction and combinations of parts hereinafter fully described, illustrated 25 in the accompanying drawing, and specifically claimed.

In the accompanying drawing, like characters of reference indicate like parts in the several views, and:—

Figure 1 is an elevation of a gas fixture 25 having the gas bell hanger applied thereto.

Fig. 2 is an enlarged detail section 30 through a sliding joint, as used herewith.

Fig. 3 is a top plan view of certain sockets 35 for adjusting the angularity of the arms, as used herewith.

Fig. 4 is an enlarged side view of the 40 clamp which fits on the vertical member of the gas fixture.

Fig. 5 is a plan view of the device as 45 shown in Fig. 4.

Fig. 6 is an enlarged detail view of the 50 connecting joint of the clamps used herewith.

In carrying out the objects of this invention and as shown in the drawings herein set forth, there is indicated a gas fixture F having a central post or supply pipe P. On 55 this supply pipe is fitted a clamp which

consists of a semi-circular member 10 having at one end a pair of hinge eyes 11 and at the other end a projecting lug 12 provided with a slot 13. The clamp furthermore has a second semi-circular member 14

55 provided with a hinge ear 15 and through

the ears 11 and 15 passes a pivot bolt 16. The last-mentioned member 14 is provided with other hinge ears 17 to which is pivotally connected an arm 18 having an opening 19 therethrough for the reception of a bolt 20 provided with a nut 21. By means of this construction the nut may simply be loosened and the arm 18 swung out as shown in Fig. 6 so as to free the two halves 10 and 14 at one side from each other and thus permit the clamp to be opened for application and removal. At the center of each half 10 and 14 the clamp is provided with a vertical elongated lug 22, each lug having a polygonal opening 23 extending therethrough, the 60 opening being preferably octagonal. The arms of the hanger consists of inner tubular members 24 having downturned ends 25 polygonal in cross section so as to fit the openings 23. Slidable in these tubular arms 25 are rods 26 having upturned ends 27 so that 65 bells 28 may be hung thereon over the burners B of the fixture F. These arms 26 are held in adjusted position within the tubular members 24 by set screws 29.

Now it will be observed that by proper manipulation of the set screws and arms 26 and 24 the bells may be adjusted to extend inwardly or outwardly as desired and that by setting the ends 25 at different angles in 70 the openings 23 the arms may be angularly adjusted with reference to the clamp. This is advisable in many instances wherein the pipe P is not circular in cross section because it frequently happens that the clamp can not 75 be applied to the pipe in the exact position desired unless it is necessary to set the arms 24 and 26 at proper angles.

There has thus been provided a simple 80 and efficient device of the kind described 85 and for the purpose specified.

It is obvious that many minor changes 90 may be made in the form and construction of the invention without departing from the material principles thereof. It is not therefore desired to confine the invention to the exact form herein shown and described but it is wished to include all such as properly come within the scope claimed.

Having thus described the invention what 95 is claimed as new, is:—

In a device of the kind described, a pipe 100 clamp comprising a pair of semi-circular members, one end of one member being hingedly connected to the adjacent end of 110

the other member, the free end of the last-named member provided with a projecting lug having a slot formed therein, an arm hingedly connected to the free end of the 5 first-named member and adapted to be moved in parallelism with the projecting lug of the other member, said arm provided with an opening registering with the slot of the lug, means extending through the 10 opening and slot of the respective members to hold the same against outward swinging

movement and a radially extending lug formed integral with the convex side of each semi-circular member centrally thereof, said lugs provided with openings which are substantially polygonal in cross section for the purpose specified. 15

In testimony whereof I affix my signature.

PAUL J. WIDERA.
